Primary Examiner — Randall Gholson

(57) **CLAIM**

The ornamental design for a mower deck leveling tool, as shown and described.

DESCRIPTION

FIG. 1 is the perspective view of the mower deck leveling tool.

FIG. 2 is the top view of the mower deck leveling tool; and, FIG. 3 is the bottom view of the mower deck leveling tool. The left and right sides of the mower deck leveling tool are flat and include no surface ornamentation.

1 Claim, 3 Drawing Sheets

FIG. 2

FIG. 3
